UNITED STATES PATENT OFFICE.

CHESTER D. ZUMWALT, OF CENTER, MISSOURI.

ARMORED AUTOMOBILE.

1,191,380.

Specification of Letters Patent. Patented July 18, 1916.

Application filed September 22, 1915. Serial No. 52,019.

To all whom it may concern:

Be it known that I, CHESTER D. ZUMWALT, a citizen of the United States, residing at Center, in the county of Balls, State of Missouri, have invented certain new and useful Improvements in Armored Automobiles; and I do hereby declare the following to be a full, clear, and exact description of the invention, such as will enable others skilled in the art to which it appertains to make and use the same.

This invention relates to armored automobiles.

The object of this invention resides in the provision of an armored automobile embodying an improved construction whereby the efficiency of the same as an offensive weapon is materially enhanced.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a side elevation partly in section of an armored automobile constructed in accordance with the invention; Fig. 2, a section on the line 2—2 of Fig. 1; Fig. 3, a partial longitudinal section; Fig. 4, a horizontal section; Fig. 5, a fragmental perspective view of one of the firing shafts; Fig. 6, an end view of one of the firing shafts; Fig. 7, a section on the line 7—7 of Fig. 2, and Fig. 8, a section on the line 8—8 of Fig. 7.

Referring to the drawings the invention is shown as comprising a body A supported upon wheels 10 in any suitable manner and adapted to be propelled by means of a suitable motor 11. The body A is of the armored type and comprises side members 12 and 13, a rear member 14 and a front member 15. The rear member 14 includes a door 16 through the medium of which access to the interior of the body may be had. The body further comprises a floor 17 of any desired construction suitable for the service to be performed thereby. The forward portion of the body A is inclined as at 18 and provided with observation ports

19 adapted to be closed by means of shutters 20. The front portion of the body is also provided with a gun port 21 through which projects a gun 22 mounted upon a rotatable base 23. The gun 22 embodies the usual trunnions 24 to one of which is secured a hand lever 25. An arm 26 is also secured to the same trunnion for a purpose that will presently appear. Pivoted upon the base 23 is a foot lever 27 provided with a pedal 28 and connected to the arm 26 by means of a link 29. By this construction it will be obvious that the base 23 can be rotated through the medium of the lever 25 while the gun 22 can be elevated by the manipulation of the lever 27, the lever 25 serving to effect lowering of the gun as will be obvious.

Mounted upon the floor 17 adjacent each side of the body A are brackets 29 and 30 in which are mounted rods 31 running longitudinally of the body A and disposed one above the other. The rods 31 are rotatably engaged with the brackets 29 and 30 and each of said rods has fixed thereon a plurality of guns 32 which project through suitable ports 33 in the adjacent side member of the body. The guns on the upper rod 31 are mutually connected by a rod 34, while the guns on the lower rod 34 are mutually connected by a rod 35 and these rods 34 and 35 are connected by a link 36 provided with a lateral extension 37 serving as a training handle. This extension 37 is provided with a tubular portion 38 through which is slidably engaged a rack bar 39 pivoted upon the floor 17. The tubular portion 38 has mounted therein a spring latch 40 adapted to cooperate with the rack bar 39 to lock the guns 32 in a desired position for firing. From this construction it will be obvious that the guns 32 on each side of the body A can be properly sighted by manipulating the handle or extensions 37.

Each of the guns 32 includes the usual trigger 43. The guns carried by the upper rod 31 have rotatably connected therewith in advance of the triggers 43 a firing shaft 44, while a similar firing shaft 45 is associated with the guns 32 carried by the lower rod 31. Each of the shafts 44 and 45 is provided with trigger engaging fingers 46 so arranged that the rotation of said shafts will fire the associated guns successively instead of in volley. The shafts 44 and 45 are adapt-

ed to be manually rotated through the medium of cranks 47 mounted on corresponding ends of said shafts respectively.

What is claimed is:—

- 5 1. In an armored automobile, the combination with the wheeled body, of a pair of shafts rotatably mounted within the body and extending longitudinally of the latter, said shafts being disposed one above the other, a plurality of guns fixed on each shaft and projecting through ports in the body, a second pair of shafts mutually connecting the guns carried by the first named shafts respectively, a link connecting the second named shafts, an arm on said link whereby the first named shaft may be manually rotated to train the guns carried thereby, and means co-operating with said arm to hold the first named shafts against rotation.
- 10 15 20 2. In an armored automobile, the combination with the wheeled body, of a plurality

of guns pivotally mounted within the body for movement in a vertical plane, a trigger included in each gun, a rotatable shaft mutually connecting said guns and disposed in advance of said triggers, arms on said shaft for engaging the triggers when the shaft is rotated, means for rotating said shaft connections between the guns for effecting simultaneous pivotal movement thereof, an arm carried by said connections, a tubular portion included in said arm, a rack bar pivotally secured to said body and slidable through the tubular portion, and a spring latch carried by the tubular portion for co-operating with the teeth of said rack bar.

In testimony whereof, I affix my signature, in the presence of two witnesses.

CHESTER D. ZUMWALT.
